MACHINE FOR APPLYING AND DRYING
ADHESIVE ON PAPER GOODS

Edwin G. Staude, Minneapolis, Minn.

Application April 6, 1942, Serial No. 437,764

18 Claims. (Cl. 91—18)

This invention relates to improvements in my previous machines and methods, which are covered by Patent 2,139,605, Patent 2,248,255, and Patent 2,261,782.

The object of my present invention is to provide a gum applying and drying apparatus for the sealing flaps of envelopes which is greatly simplified and more compact, cheaper to manufacture and much easier to operate and keep clean.

A further important object is to provide means for returning the surplus adhesive drying material in addition to small portions of new material to the dust or powder applying mechanism so that the material may be used over and over automatically as required.

A further object is the introduction of small air currents providing suction at the opening of the mechanism through which the article to be treated enters and leaves so that very fine particles of dust will remain inside of the unit, or if the turbulence is too great, exhausted into a suitable vacuum cleaner bag.

A further object is to provide a construction that will permit the removal of the surplus dry powdered adhesive through the use of quickly removable, revolving mohair covered discs, wheels or brushes, or other suitable means by deflecting the part that is treated at an angle to the plane of travel so that the surplus powder removing discs or wheels may easily reach to the creased line on which a fold may be made later without interfering with the blank carrying mechanism.

A further object is the manner of inducing a dragging and wiping action by the blank deflecting member before the surplus dry powder is removed, the purpose of which is to work the dry powdered adhesive into the wet adhesive thoroughly before wiping off the surplus, in order to absorb most of the free moisture and obtain a sufficiently heavy application of adhesive after the surplus dry powder has been removed.

A further object is to provide a suitable agitating device within the compartment of the adhesive dusting mechanism to prevent plugging up or packing of the powdered adhesive and insure a continuous free flow of the adhesive powder to the dusting mechanism.

Other objects, features and advantages of the invention will appear in the description of the drawings and be further pointed out in the claims. Various modifications may obviously be devised without departing from my invention and I, therefore, do not limit my invention to the precise construction shown.

Fig. 1 is a plan view showing my invention at

tached to an envelope gluing and folding machine, similar to my Patent 1,144,506, in such manner as to constitute a new and improved method of gumming and drying the sealing flaps of envelopes at greatly increased production efficiency and reduced cost.

Fig. 2 is an outside view of the casing enclosing the improved glue dusting mechanism of my present invention, and

Fig. 3 is a front end view of said casing, while Fig. 4 is a rear view thereof with its rear wall removed to expose the mechanism therein.

Fig. 5 is a sectional view, taken on line 5—5 of Fig. 4 through the upper part of the casing, and showing in enlarged detail the construction of the vibrating hopper and the powdered glue distributing roll.

Fig. 6 is a plan view showing the top of the casing cut away to expose the mechanism as it appears when glue dusting a series of fast-moving envelopes.

Fig. 7 is a horizontal section, on the line 7—7 of Fig. 8, through the upper part of a transmission gear box, which is mounted in the duster unit casing.

Fig. 8 is a vertical section on line 8—8 of Fig. 7, and

Fig. 9 is a cross-section on line 9—9 of Fig. 8.

Fig. 10 is an end view of the improved wiping roll employed, and

Fig. 11 is a cross-section through said wiping roll as it appears in action on an envelope flap.

Fig. 12 is a detail view showing means for vibrating the powder delivery hopper, while

Fig. 13 is a detail view of the eccentric hub which imparts the vibratory movement to said hopper, and

Fig. 14 is a similar view of a sprocket having an eccentric hub which imparts oscillating motion to an agitating device which prevents packing and accumulation of the glue powder within said casing.

Fig. 15 is an isometric perspective view showing in a diagrammatic manner the improved method of applying the gum or glue to the bottom flap and the sealing flap and method of applying the powdered adhesive, the manner of deflecting the sealing flaps and working in the dry adhesive into the wet adhesive and the means of removing the surplus dry powdered adhesive and folding both end flaps of the envelopes during a single straightaway passage through the rear section of the machine.

Fig. 16 is a front-end view of the mechanism

used for applying wet adhesive to the envelope flaps, and

Fig. 17 is a side-view of same, partially in section.

Fig. 18 shows how a means may be provided for creating a slight sub-atmospheric pressure in the duster unit casing at the openings of the casing or compartment through which the article to be treated passes.

Fig. 19 is a side-view of same, taken on the line 19—19 of Fig. 18.

In Fig. 1, I have shown a plan view of an envelope making machine, somewhat similar to that shown and described in my adjustable envelope machine Patent 1,144,506, wherein a supply of envelope blanks *a* are disposed in a hopper *b* where feed wheels *c* feed the uppermost blank and propel it rearwardly past a lower glue applying and folding mechanism *d* and *e* which deposits moist glue on one under edge thereof and turns both side flaps inwardly to become joined in overlapped relation while it travels to a stop against a cross-bar *f*. At this point, the transversely moving chains *g* carry the partly folded blanks laterally past glue applying means *h*—*h* which deposit a film of moist glue on the edge of both end flaps thereof, while they are conveyed by means *i*—*i* past right side folding means *j* and left side folding means *k* which turn both end flaps inwardly just before the then completed envelope enters the stacking means *l* where they are accumulated in a vertical stack *m*. Of course, when this envelope making machine is operated without the improved glue dusting unit, which forms the subject matter of this application, the left side glue applying means *h* is moved out of contact with the passing blanks so that no adhesive will be deposited on the sealing flap *o* thereof, and these unfinished envelopes must then be passed through a second glue applying machine, which is provided with special glue drying means, for applying and drying adhesive on the sealing flap *o* or the operation of applying and drying adhesive on the sealing flap may be accomplished before the blank is fed into the hopper *b*. However, many types of envelopes are used without gummed sealing or closure flaps and may be thus completed on the above described machine, in which case my improved glue dusting unit may be easily and quickly removed from the machine frame to which it is secured by bolts *p*.

As shown in Fig. 1, my present glue dusting unit is located on the left side of the right angle section of the machine, immediately in the rear of the glue applying means *h*, where the fast-moving series of spaced envelopes blanks are firmly gripped by the conveyors *i*—*i* while they are carried rearwardly with their sealing flap *o* extending into said glue dusting unit, as further illustrated by Fig. 6.

The improved glue dusting unit consists of a casing or supply chamber *W* having a sheet metal front panel *15* (see Figs. 2—5—6—7—9) to which a cast metal frame *16* is secured and adapted to support a motor *17* at its outer end and a transmission gear box *18* (see Fig. 7) at its inner end. A spout *19* (see Figs. 2—3) is also provided on the panel *15* into which a supply of powdered glue or other dried powdered adhesive may be poured into the interior of the casing or dry powdered adhesive supply chamber for replenishing and a hinged cover *20* is arranged to close the upper end of said spout. A transparent window *21* is also provided in the panel *15*, while an upper rear corner section *15'* is hinged to said panel at *15''*

and adapted to be held in closed position by a latch *22*. (See Fig. 2.)

Sheet metal end walls *23* are detachably secured to the rear edge of the panel *15* and extend to and form a part of the rear wall *24* which is thereby spaced from the panel *15* so as to form an enclosed compartment adapted to contain the powdered adhesive and the mechanism for properly applying same to the envelope sealing flap. Angle brackets *25* are secured to the end walls *23* at opposite ends of the casing and support said casing in position on the frame *s* of the machine, as shown in Fig. 1, and sheet metal guide brackets *26* are disposed above the brackets *25* and have a flattened passage *27* leading to a slit in the end walls *23* at each end of the casing. (See Fig. 3.)

The rear wall *24* has a longitudinal slit *28* which registers with the slits at both ends of the casing or supply chamber and strips *29* of a brush-like fabric such as long pile mohair are oppositely attached to the rear wall *24* so as to yieldingly cover said longitudinal slit, as shown in Fig. 5. A hinged cover *30* is adapted to close a discharge opening *31* in the bottom of the casing or supply chamber for use when it is desired to empty the contents of the compartment or supply chamber while a transparent inspection plate *32* is hinged above an opening in the top of said casing.

Within the casing, angular metal strips *33* are attached to the inside of the front wall *23* at the front end of the casing or supply chamber so as to form a vertical passage *34* in which a series of elevator flights *35* are adapted to carry the powdered adhesive *36* from the bottom to the top of said casing or supply chamber.

The flights *35* are attached at short intervals to a chain *37* (see Fig. 4), which passes around sprockets *38* and *39*, located respectively at the bottom and top of the vertical passage *34* and are mounted on studs *40* and *41* which are secured in the front panel *15*.

The chain *37* is driven by a sprocket *42* (see Fig. 7) which in turn is driven by transmission gearing as hereinafter described, while said chain also passes over an idle sprocket *43* on a stud *44* near the bottom rear end of the casing, where said stud is attached to a chain tightening device consisting of an arm *45* on a short shaft *46* which extends through a bearing in the panel *15* and has a short arm *47* on its outer end, which contacts a set screw *48* whereby said device may be adjusted to take up the slack in said chain.

The dry powdered adhesive normally is a flour-like substance which will not flow freely but will pack quickly so the elevator flights *35* will work a tunnel through the powdered adhesive and soon cease to function. In order to avoid this, I provide an agitating device which I describe as follows:

The sprocket *38* is provided with an eccentric hub *49* from which a connecting rod *50* extends to a crank pin *51* on a hub *52* which is mounted on a stud *53* in the central part of the casing, and a number of spokes *52'* radiate from the hub *52* to form an agitating device which is adapted to continually loosen any formation of powder which may pack therein so as to insure its gravitation to the bottom of the casing where the horizontal stretch of elevator chains *37* will move said powder toward the vertical passage *34*.

The gear box *18* (see Figs. 7—8—9) has bearings *54* and *55* for a shaft *56* which is connected by a coupling *57* to the motor shaft *58*, and a spiral gear *59* on the shaft *56* transmits right

angle motion to a mating spiral gear 60 which is secured to a longitudinal shaft 61 extending through bearings 62 and 63 at opposite ends of the gear box 18. A worm 64 is also secured to the shaft 61 and meshes with a worm gear 65 on an over-head cross-shaft 66 which is journaled in bearings 67 and 68 and carries the sprocket 42 on its outwardly projecting end. The front end of the shaft 61 extends beyond the gear box and carries a corrugated roll 69 having eccentric hubs 70, and a disc having fan blades 71 is clamped against the outer end of said shaft. Plates 73 and 74 are spaced apart to enclose the corrugated portion of the roll 69 and are bored to a running fit on the eccentric hubs 70 thereon, and a sheet metal hopper 75 is mounted on said plates and is adapted to direct the powder on to the upper part of the corrugated roll (see Fig. 5).

The hopper 75 has a curved portion 75' and a cooperating curved member 76 has a beveled lower edge which may be adjusted to any desired point below the edge of the curved portion 75' by a clamping bolt 77 which extends through a curved slot 78 in the flange 79 to which the curved member 76 is secured.

The purpose of the beveled lower edge of the member 76 is to permit adjustment of the delivery of the dry powdered adhesive uniformly over the entire area of the wet adhesive on the sealing flap *o*. This is accomplished by making the outlet of the member 76 either on a 30 degree bevel or even a V shaped outlet (see Figs. 4-5).

With this construction certain portions of the dry powdered adhesive will be released tangent from the member 69 while other portions depending on the degree of bevel will be released later thus applying a uniform layer of dry powdered adhesive over the entire area of the wet adhesive on the sealing flap *o*.

One side wall of the hopper has a looped upper edge 80 embracing a fixed rod 81, which forms a pivot to allow the entire hopper to be oscillated rapidly by the eccentric 70 so as to insure positive delivery of the powder therein to the corrugated roll 69 as shown in Figs. 5 and 12, and a roller 82 is mounted on a pin 83 at the upper edge of the hopper and is adapted to transmit the vibratory motion to the chain 37 so as to shake the powder from the elevator flights into said hopper, where it is engaged by the corrugated roll 69 and sprayed into the passage through which the sealing flap *o* passes.

The rear end of the shaft 61 extends beyond the bearing 63 and has a spline 84 entering keyways in a number of separable rolls 85 which have a flanged periphery accommodating a belt 86 of brush-like fabric, such as long pile mohair, and these rolls are held in position on the shaft by an annular projection 87 on the hinged corner section 15'.

A fan disc 88 on the collar 89 is keyed on the shaft 61 between the rolls 85 and the rear end of the gear box, as shown in Figs. 7 and 8, and a twisted deflector bar 90 for deflecting the sealing flap *o* is secured to the under side of said gear box by the cover clamping screws 91, as shown in Figs. 8 and 9. A curved shoe 92 (see Figs. 4-5) is arranged beneath the rolls 85 and is supported by arms 93 which are hinged at 94 on the inside of the panel 15, as shown in Fig. 5, and a depending portion 95 on one of said arms engages a set screw 96 which may be adjusted from the outside of the casing to elevate said shoe into contact with the under side of the rolls, for the purpose hereinafter described.

Fig. 15 graphically explains the essential features of my invention, which include: means for moving a continuous procession of spaced envelope blanks while they are treated consecutively at separate points or stations during their passage through the machine, wherein at point A the end flaps of the partially folded envelope blanks *a* receive a film of moist adhesive from the rotating glue wheels *h-h*; at point B one glue coated flap is being folded by suitable means *j*, while the other moist glue-coated flap is being covered with a layer of powdered dry adhesive 36; at point C one flap is completely folded over while the powdered flap is deflected downwardly by the spiral shaped bar 90 which drags over the dry powder and works same into the wet adhesive and directs the flap *o* to pass beneath the rolls 85 where the surplus powder is wiped from said flap *o* and the remaining powder adhering to the wet adhesive is further worked into the moist adhesive by the wiping action of the brush-like fabric covering of said rolls; at point D the powder dried sealing flap *o* which no longer will adhere without re-moistening is folded over by suitable means *k*; while at point E the completed envelopes are being delivered into a vertical stack by suitable means *l*.

Fig. 11 shows how the envelope flap *o* conforms to fit the curvature of the shoe 92 and is thereby held against the rolls 85 while the rolls 85 wipe the surplus powder from said flap, and Fig. 11 also shows how the long hair-like pile of the fabric is pressed against the flap by centrifugal force so as to press the remaining powder into intimate union with the moist adhesive to absorb the moisture thereof. This combined pressing and wiping leaves the gummed sealing flap sufficiently dry to allow immediate stacking of the completely folded envelopes without any tendency of said sealing flap to adhere or "stick" to the back of said envelope.

While I speak of my invention as a drying mechanism as used particularly for drying the gum on sealing flaps of envelopes, I do not mean that any water has actually been evaporated by my method. What I do mean is that such moisture as may be in the first light application of wet adhesive is by the addition of dry powdered adhesive rendered incapable of adhering due to the lack of sufficient moisture when an additional volume of the dry powdered adhesive is added.

I have found the long-pile mohair fabric peculiarly suited for removing the surplus dry powdered adhesive because due to the high speed and centrifugal action the silky smoothness of its long pile has a natural tendency to throw off the dry powder and remain clean while wiping and working in the dry powder during the process of removing the surplus.

Due to the high speed of the members 69 for applying the dry powder adhesive and the rolls 85, a considerable dust turbulence is set up within the dry powdered adhesive supply chamber or compartment, and this dust has a tendency to escape from the slots 27 at the entrance for the flap *o* and the slot 27 and the exit of the flap *o*.

To overcome the escape of the powdered dust through the slots 27, I provide the small fan shaped member 78 at the entrance of the flap *o* with just enough suction to overcome the tendency for the dust to escape and thereby hold some within the compartment.

I also provide a similar fan 89 at the exit of the flap *o* with a similar slight suction capacity 78 to prevent the dust from escaping at the exit

of the slot 27. The slot 28 is sealed by the mohair padding 29.

With this precaution very little dust escapes from the supply chamber or compartment through the passage which must be kept open for the flap *a* to enter and leave the supply chamber or compartment.

Figs. 16 and 17 show how the envelope flaps are held up against the glue applying wheels *h*—*h* by rolls 100 journaled in the front end of arms 101, which are pivoted at 102 and provided with an adjustable stop screw 103 at their rear end, while a compression spring 104 is arranged to depress said rear end so as to yieldingly support the rolls 100 in their predetermined position beneath said glue applying wheels.

The conveyor belts *i*—*i* pass about the inner end of the rolls 100 and over anti-friction rollers 105, and a series of pressure rollers 106 are carried by an inverted channel bar 107 above the belts *i*—*i* to press the envelope blanks against said belts insuring positive movement of the blanks. Glue pots 108 are suspended from a cross-member 109 and are provided with a comparatively large glue transfer roll 110, which receives a film of wet adhesive from the smaller rolls 111 and 112, which are partly submerged in the liquid glue 113, while the pots are hinged at 114 and engaged by an eccentric 115 by which said pots may be tilted slightly with respect to the glue transfer roll 110 so that the rolls 112 and 111 will deposit a film of glue of desired thickness of said transfer roll 110.

The glue pots are adjustably mounted on the cross-member 109 so that the transfer roll 110 may be placed in position to deposit its film of glue to the glue applying wheels *h*—*h*. A train of gears 116 connect the glue pot rolls with the driven glue wheel shaft 116 so as to drive the various rolls in the direction indicated by the arrows in Fig. 17.

I may also further prevent any of the powdered adhesive dust from escaping through the slits 27 and 28 of the compartment while the envelope flaps are passing rapidly through said slits, by inducing a very slight suction within the compartment by providing a separate suction device with an air strainer bag. This may be accomplished by providing a small fan 117 (see Figs. 18—19) on the motor coupling 57 with a special motor base 118, in which an intake port 119 communicates with the interior of the compartment while an outlet port 120 leads to a downwardly extending tube 121 to which an air strainer bag 112 is removably detached.

The very low velocity air current produced in this manner is only required to slightly reduce the air pressure within the compartment to cause a slight inward flow of air through the slots 27 and 28 just sufficient to keep powdered dust from escaping through said slots and would, therefore, carry away only a comparatively small amount of the powder which would be confined in the bag from which it may be emptied periodically at convenient intervals.

The operation of my invention is as follows: The blank *a* is fed into the machine at the feed hopper and *b* (see Fig. 1) one at a time in timed relation. Adhesive is applied on the under left hand side of the blank which is folded over to make the first center seam adhesive juncture and the partly folded blank is delivered on a right angle transfer section where chains with lugs *g* move the blank at right angles past a wet adhesive applying mechanism *h* (see also Figs. 16

and 17) where wet adhesive is applied to the bottom flap which is immediately folded by the bar *j* (see Fig. 15) and also to the sealing flap.

The blank then passes into the slot 28 (see Fig. 5) where dry powdered adhesive is dusted upon the freshly applied wet adhesive by the fast revolving fluted member 69.

The sealing flap is then deflected by the member 90 which directs the flap against the periphery 11 of the surplus dry powder adhesive removing member 85 which surplus dry powdered adhesive falls to the bottom of the casing or supply chamber *w* because the sealing flap is held against the member 85 by the concave member 92.

The supply chamber contains the elevator chain 37 having flights 35 which elevate the dry powdered adhesive supply from the bottom of the supply chamber or casing *w* to the hopper 75 (see Fig. 5) where the cycle is again repeated.

To keep the dry powdered adhesive in constant flowing condition I provide the agitators 52'.

I do not limit the scope of my invention to the precise construction shown because various modifications may be devised without departing from my invention.

I believe I am the first to successfully apply and dry adhesive to flat surfaces in a manner acceptable to the trade and I therefore claim a broad interpretation of the invention herein set forth.

As a modification of the dusting mechanism including the vibrating hopper 75, I may provide a brush with its axis parallel with the travel of the elevator chain 37 and mounted above the chain 37 at the discharge point and brush out the dry powdered adhesive between the flights 35 and deliver the dry powdered adhesive directly to the wet adhesive area of the envelope flap thereby doing away with the vibrating hopper 75 and its associated mechanism. Instead of a chain for elevating the dry powdered adhesive I may use a disc wheel having notches on its periphery to pick up the dry powdered adhesive and use the brush likewise to clean out the dry powdered adhesive in the notches and deliver the powder directly to the wet adhesive area.

I claim:

1. In an envelope making machine including a sealing flap gumming and drying mechanism for applying adhesive to the sealing flaps of envelopes and conditioning said adhesive against adhering without remoistening, comprising means for advancing said envelopes; means for applying wet adhesive to said sealing flap; a chamber for holding a supply of dry powdered adhesive, a slot on the side of said chamber for the passage of said sealing flaps within said chamber, means within said chamber for applying dry powdered adhesive to said wet adhesive on said sealing flap; means for removing the surplus dry powdered adhesive; means for returning the said surplus dry powdered adhesive together with the required additional dry powdered adhesive to the means for applying dry powdered adhesive; driving connections for the moving members within said chamber.

2. In an envelope making machine including a sealing flap gumming and drying mechanism for applying adhesive to the sealing flaps of envelopes and conditioning said adhesive against adhering without remoistening, comprising means for advancing said envelopes; means for applying wet adhesive to said sealing flap; a chamber for holding a supply of dry powdered adhesive, said chamber having a slot for the pas-

sage of said sealing flap into and out of said chamber; means including an intake hopper within said chamber for applying dry powdered adhesive to said wet adhesive on said sealing flap; means for removing the surplus dry powdered adhesive together with the required additional dry powdered adhesive to the intake hopper of the means for applying dry powdered adhesive; an agitating device to cause free flowing of said dry powdered adhesive to said means for returning the said surplus dry powdered adhesive to the intake of the means for applying dry powdered adhesive; driving connections for the moving members within said chamber.

3. In an envelope making machine including a sealing flap gumming and drying mechanism for applying adhesive to the sealing flaps of envelopes and conditioning said adhesive against adhering without remoistening, comprising means for advancing said envelopes; means for applying wet adhesive to said sealing flap; a chamber for holding a supply of dry powdered adhesive and having a slot for the passage of said sealing flap into and out of said chamber, means within said chamber for agitating said dry powdered adhesive; means within the chamber for applying dry powdered adhesive to said wet adhesive on said sealing flap; means for removing the surplus dry powdered adhesive from said sealing flap; means for returning the said surplus dry adhesive together with the required additional dry powdered adhesive to the means for applying dry powdered adhesive including a slow moving sprocket chain provided with elevator flights; driving means for the moving members within said chamber.

4. In an envelope making machine including a sealing flap gumming and drying mechanism for applying adhesive to the sealing flaps of envelopes and conditioning said adhesive against adhering without remoistening comprising means for advancing said envelopes; means for applying wet adhesive to said sealing flap; a chamber for holding a supply of dry powdered adhesive, said chamber having a slot for the passage of said sealing flap into and out of said chamber; a means within said chamber for applying dry powdered adhesive to wet adhesive on said sealing flap; means within said chamber for deflecting said sealing flap from the normal path of travel; means within said chamber for removing the surplus dry powdered adhesive from said sealing flap while said sealing flap is deflected from its original path of travel; driving connections for the moving members within said chamber.

5. In an envelope making machine including a sealing flap gumming and drying mechanism for applying adhesive to the sealing flaps of envelopes and conditioning said adhesive against adhering without remoistening, including means for advancing said envelopes, comprising: means for applying wet adhesive to said sealing flap; means for applying dry powdered adhesive to said wet adhesive on said sealing flap; means for removing the surplus dry powdered adhesive; a concave member for holding said envelope sealing flap against said means for removing the surplus dry powdered adhesive.

6. In an envelope making machine including a sealing flap gumming and drying mechanism for applying adhesive to the sealing flaps of envelopes and conditioning said adhesive against adhering without remoistening, comprising means for advancing said envelopes: means for applying

wet adhesive to said sealing flap; a chamber for holding a supply of dry powdered adhesive, said chamber having a slot for the passage of said sealing flap into and out of said chamber; means within said chamber for applying dry powdered adhesive to wet adhesive on said sealing flap; means within said chamber for deflecting said sealing flap below the path of travel of said blank; means within said chamber for removing the surplus dry powdered adhesive including a concave member for holding said deflected sealing flap against said dry powdered adhesive removing means; means for returning said surplus dry powdered adhesive together with the required additional dry powdered adhesive to the means for applying dry powdered adhesive; driving connections for said moving members.

7. In an envelope making machine including a sealing flap gumming and drying mechanism for applying adhesive to the sealing flaps of envelopes and conditioning said adhesive against adhering without remoistening, comprising means for advancing said envelopes, means for applying wet adhesive to said sealing flap; a chamber for holding a supply of dry powdered adhesive, said chamber having a slot for the passage of said sealing flap into and out of said chamber; means within said chamber for applying dry powdered adhesive to said wet adhesive on said sealing flap including a fast revolving fluted member, a hopper for said fluted member; means for vibrating said hopper; means within said chamber for removing the surplus dry powdered adhesive from said sealing flaps.

8. A paper fabricating machine adapted to produce an article having a gummed surface which is sufficiently lacking in moisture to prevent adhesion without remoistening, comprising: means for advancing said article; means for applying wet adhesive to said article; a chamber having a slot on one side for the passage of articles; means within said chamber for applying dry powdered adhesive to the wet adhesive on said article; means within said chamber for removing surplus dry powdered adhesive from said article; means within said chamber for agitating said dry powdered adhesive; means within said chamber including an endless carrier belt, for returning the said surplus dry adhesive together with the required additional dry powdered adhesive to the means for applying dry powdered adhesive; driving connections for the moving members.

9. A machine for applying and drying adhesive to an article having a flat surface, comprising: means for advancing said article; means for applying a liquid adhesive to a predetermined area of said article; a chamber having a slot on one side for the passage of articles, means within said chamber including a single revolving member operating at high speed for applying dry powdered adhesive over the liquid adhesive to remove the adhesive characteristic; means within said chamber for removing the surplus dry adhesive; means within said chamber for returning the surplus dry powdered adhesive to the means for applying dry powdered adhesive; driving connections for the moving members.

10. A machine for applying and drying adhesive to an article having a flat surface comprising: means for advancing said article; means for applying liquid adhesive to a predetermined area of said article; a chamber for holding a supply of dry powdered adhesive, a slot on one side of said chamber to permit the entrance and

exit of a portion of said article means within said chamber for applying dry powdered adhesive over the liquid adhesive to remove the adhesive characteristic; means within said chamber for deflecting a portion of said article from the normal path of travel; means within said chamber for removing the surplus dry powdered adhesive; concave means within said chamber for holding said deflected portion of said article against said surplus removing means; a dry powdered adhesive agitator within said chamber to prevent packing of said dry powdered adhesive; means within said chamber for returning said surplus adhesive together with the required additional dry powdered adhesive to the means for applying the dry powdered adhesive; driving means for the moving members.

11. A machine for applying and drying adhesive to an article having a flat surface comprising: means for feeding said article; means for applying wet adhesive to predetermined areas of said article; a chamber for holding a supply of dry powdered adhesive, a slot on one side of said chamber to permit the entrance and exit of a portion of said article, means within said chamber for applying dry powdered adhesive over said wet adhesive including a fast revolving member mounted within an intake hopper having an open end; means for vibrating said hopper; a curved member within said chamber for deflecting the adhesive treated portion of said article; rotating discs within said chamber provided with brushing material on the periphery of said discs for removing the surplus dry powdered adhesive; a concave member within said chamber for holding said deflected portion of said article against the brushing material on said discs; an elevator within said chamber for returning the surplus dry powdered adhesive together with the required additional dry powdered adhesive to the intake hopper of the means for applying the dry powdered adhesive; an agitator within said chamber to prevent packing of said dry powdered adhesive; driving means for the moving members.

12. A machine for applying and drying adhesive to an article having a flat surface comprising: means for advancing said article; means for applying wet adhesive to predetermined areas of said article; means for applying dry powdered adhesive over said wet adhesive; means for removing surplus dry powdered adhesive from predetermined areas of said articles; a chamber enclosing the said means for applying dry powdered adhesive and said means for removing the surplus; slots in said chamber to permit entering of the wet adhesive portion of said flat article and leaving same; driving means for the moving members.

13. A machine for applying and drying adhesive to an article having a flat surface including advancing means for said article, comprising: means for applying wet adhesive to predetermined areas on said article; means for applying dry powdered adhesive over said wet adhesive; means for removing surplus dry powdered adhesive from predetermined areas of said articles; a chamber enclosing the said means for applying dry powdered adhesive and said means for removing the surplus; slots in said chamber to permit entering of the wet adhesive portion of said flat article and leaving same; suction apparatus for causing a slight suction on the inside of said chamber near said slots to prevent escape of dust particles through said slots during

the normal operation of the machine; driving means for the moving members.

14. A machine for applying and drying adhesive to an article having a flat surface including advancing means for said article, comprising: means for applying wet adhesive to predetermined areas on said article; means for applying dry powdered adhesive over said wet adhesive; means for removing surplus dry powdered adhesive from predetermined areas of said articles; a chamber enclosing the said means for applying dry powdered adhesive and said means for removing the surplus; slots in said chamber to permit entering of the wet adhesive portion of said flat article and leaving same; suction apparatus including an air strainer bag for causing a slight suction on the inside of said chamber near said slots to prevent escape of dust particles through said slots during the normal operation of the machine; driving means for the moving members.

15. A machine for applying and drying adhesive to an article having a flat surface including advancing means for said articles, comprising: means for applying wet adhesive to predetermined areas on said article; a chamber for holding a supply of dry powdered adhesive; a slot on one side of said chamber to permit the entrance and exit of a portion of said articles; means within said chamber for applying dry powdered adhesive over said wet adhesive; means for removing surplus dry powdered adhesive from predetermined areas of said articles; a driven shaft located within said chamber and having its axis parallel with the direction of travel of said article through the machine; connections on one end of said shaft for operating said means for applying dry powdered adhesive; connections on the opposite end of said shaft for operating the said means for removing the surplus dry powdered adhesive; a driving gear on said shaft having right angle gear connections with a suitable source of power.

16. A machine for applying and drying adhesive to an article having a flat surface including means for advancing said article comprising: means for applying wet adhesive to predetermined areas of said article; a dry powdered adhesive supply chamber; slots in said chamber to permit entering and leaving of a portion of said article; flexible means for sealing said slots to permit the passage of a part of said article and prevent escape of surplus dry powdered adhesive; means within said dry powdered supply chamber for spraying dry powdered adhesive over said wet adhesive; a high speed rotary member for removing the surplus dry powdered adhesive from said article; an oscillating member within said chamber to prevent said dry powdered adhesive from packing; means for elevating said dry powdered adhesive from the bottom of said chamber to supply said means for spraying dry powdered adhesive over said wet adhesive; driving means for the moving members.

17. A machine for applying and drying adhesive to an article having a flat surface including means for advancing said article, comprising: means for applying wet adhesive to predetermined areas of said article; a chamber for holding a supply of dry powdered adhesive, a slot on one side of said chamber to permit the entrance and exit of a portion of said article; a high speed revolving member within said chamber for spraying dry powdered adhesive over said wet adhesive; a spiral-shaped member

within said chamber for deflecting a portion of said article; high speed rotary member within said chamber for removing the surplus dry powdered adhesive; a concave member within said chamber for holding a part of said article against said high speed rotary member; an oscillating member within said chamber to prevent said dry powdered adhesive from packing; an elevator within said chamber including an endless belt for elevating said dry powdered adhesive to supply said single high speed revolving member; driving connections for said moving members.

18. In an envelope making machine including a sealing flap gumming and drying mechanism for applying adhesive to the sealing flaps of envelopes and conditioning said adhesive against adhering without remoistening, comprising means for advancing said envelopes, means for applying wet adhesive to said sealing flap; a chamber for holding a supply of dry powdered

adhesive; a slot on one side of said chamber to permit the entrance and exit of said sealing flap; means within said chamber for applying dry powdered adhesive to wet adhesive on said sealing flap; means within said chamber for deflecting said sealing flap below the path of travel of said blank; means within said chamber for removing the surplus dry powdered adhesive; means within said chamber for holding said deflected sealing flap against said dry powdered adhesive removing means; means within said chamber for returning said surplus dry powdered adhesive together with the required additional dry powdered adhesive from the bottom of said chamber to the means for applying dry powdered adhesive; suction fan located within said chamber near the entrance and exit of said sealing flap into said chamber; driving connections for said moving members.

EDWIN G. STAUME.
